UNITED STATES PATENT OFFICE.

EDGAR E. BROSIUS, OF PITTSBURGH, PENNSYLVANIA.

BILLET-HANDLING APPARATUS.

Application filed March 31, 1923. Serial No. 629,005.

The present invention relates broadly to furnace charging machines, and more particularly to a charging machine of the type adapted for handling slabs, billets and the like.

For the purpose of charging slabs, billets, and the like, into furnaces, removing the same therefrom, and delivering them to a roll table, it has heretofore been customary in the art to provide comparatively heavy and cumbersome apparatus. Such apparatus is not only expensive, but requires the expenditure of a large amount of power for operating the same. By the present invention there is provided an extremely light and flexible apparatus of such construction that the component parts may conveniently be carried in stock and assembled in accordance with orders and specifications received.

For the sake of brevity, the term "billet" will be used throughout the specification and claims in its generic sense for the purpose of defining the material being handled, it being understood that the term is not used in an exclusive sense.

In the accompanying drawings there are shown for purposes of illustration certain preferred embodiments of the present invention, it being understood that the drawings do not define the limits of my invention and that changes may be made in the construction and operation herein disclosed without departing from the spirit of the invention or the scope of my broader claims.

In the drawings:

Figure 1 is a top plan view, partly in section and largely diagrammatic illustrating a billet charging machine, embodying the present invention, in a plurality of different operative positions;

Figure 2 is a vertical sectional view on the line II-II of Figure 1;

Figure 3 is an end elevation of the construction illustrated in Figure 2, this view showing more particularly the operator's platform and the various controls;

Figure 4 is a detail view, partly in section and partly in elevation, illustrating a portion of the bridge crane construction;

Figure 5 is a vertical sectional view on the line V-V of Figure 4;

Figure 6 is a detail sectional view illustrating another portion of the crane construction;

Figure 7 is a vertical sectional view on the

line VII-VII of Figure 1, looking in the direction of the arrows;

Figure 8 is a vertical sectional view on the line VIII-VIII of Figure 7, certain of the parts being broken away and certain of the parts being shown in elevation;

Figure 9 is a top plan view, partly broken away, illustrating a portion of the trolley;

Figure 10 is a side elevation of a portion of the construction illustrated in Figure 9, showing the hoisting mechanism and the crane trolley propelling mechanism;

Figure 11 is a detail view illustrating a portion of the rotating trolley construction;

Figure 12 is a side elevation of the construction illustrated in Figure 11;

Figure 13 is a vertical sectional view, partly in elevation, on the line XIII-XIII of Figure 14 and illustrating a portion of the hoisting drum and its operating mechanism;

Figure 14 is a vertical sectional view on the line XIV-XIV of Figure 13;

Figure 14^a is a perspective view of the mechanism illustrated in Figures 13 and 14, the upper half of the housing being swung upwardly;

Figures 15 and 16 are detail sectional views illustrating a portion of the billet gripping tongs;

Figure 17 is a detail sectional view illustrating a portion of the operating mechanism for the billet grippers;

Figure 18 is a detail view illustrating a portion of the tong mounting;

Figure 19 is a wiring diagram illustrating one manner of connecting the various controls and motors;

Figure 20 is a vertical sectional view illustrating a modified form of turning mechanism to be used in place of that shown in Figures 11 and 12;

Figure 21 is a top plan view, similar to that shown in Figure 11, of the modified turning mechanism of Figure 20;

Figure 22 is a side elevation of the construction shown in Figure 21;

Figure 23 is a vertical sectional view illustrating a modified form of trolley mechanism to be used in place of that shown in Figures 9 and 10, this view being taken on the line XXIII-XXIII of Figure 24;

Figure 24 is a side elevation of a modified form of apparatus using the trolley of Figure 23;

Figure 25 is a vertical sectional view, on an enlarged scale, on the line XXV—XXV of Figure 24;

5 Figure 25^a is a transverse sectional view on the line XXV—XXV of Figure 25;

Figure 26 is a top plan view of a modified form of billet manipulator embodying this invention;

10 Figure 27 is a side elevation of the manipulator of Figure 25;

Figure 28 is a view, similar to Figure 27, showing a slightly different form of manipulator;

15 Figure 29 is a side elevation of a modified form of horizontal manipulator;

Figure 30 is an end elevation of the apparatus shown in Figure 29, and

Figure 31 is a side elevation of another form of my invention.

20 In the illustrated embodiment of the invention I have shown, in Figure 1, one form of furnace layout in which there is a furnace 2 extending generally in one direction and a second furnace 3 extending at substantially right angles thereto. Adapted to receive the billets as they are removed from these furnaces through the charging openings 4, is a roll table 5. This table delivers the billets to the roll stands as is customary 25 in the art.

The present charging machine may be advantageously constructed in the form of a bridge crane 6 adapted to travel on overhead supporting tracks 7. The present 30 bridge crane may be of any desired construction, but is preferably of novel form which greatly facilitates the manufacture and assembly thereof by permitting the various parts to be carried in stock, thereby making it unnecessary to make a special manufacturing job of each crane.

40 The foregoing advantageous results may be secured by constructing the crane almost entirely of tubular or pipe members and of beam members. As illustrated in Figures 1, 2 and 9 of the drawings, the bridge crane may comprise side beams 8 and 9 and a center beam 10. These beams may be all cut to the desired length for the particular crane 45 being manufactured, and may be held in the desired relationship by suitable braces 11.

50 In Figures 4, 5 and 6, there is illustrated the method of mounting the supporting wheels for the crane. This construction preferably comprises end castings 12 having flat faces 13 adapted to be directly bolted to the side beams 8 and 9. Each of these castings is provided with a cut-away portion forming an angular recess having flat faces extending at substantially right angles to each other and adapted to receive bearing blocks 14 having openings therethrough for the axles 15 carrying the flanged 55 supporting wheels 16 which travel on the

tracks 7. These bearing blocks may be bolted in position in any desired manner.

Projecting from each of the castings 12 are tubular portions 17 which may be hollow if desired and of sufficient internal diameter 70 to receive therein the ends of pipes 18, or which may be of such dimensions as to form a tight fit with the interior of the pipe members as clearly shown in Figure 4. After the parts are in proper position they may 75 be secured by bolts or rivets 19. As clearly shown in Figures 1 and 4 to 6, the tubular or pipe members 18 extend transversely of the beams 8, 9 and 10. As is well known, tubular members of this character possess the 80 maximum strength for the weight of material which they contain, and they are therefore highly desirable in bridge crane work. At the same time, they provide a construction which may be easily assembled for the 85 reason that the pipe may be carried in stock cut to the required length and then readily assembled with the end pods or castings 12.

I have found that the center beam 10 may advantageously be provided adjacent each 90 end thereof with an opening 20, as shown in Figure 6, through which the pipes 18 may pass. Reinforcing and bracing flanges 22 may be secured to the center beam around the openings 20 to reinforce the structure as 95 will be apparent.

For propelling the crane along the tracks 7 I preferably provide means for driving one of the flanged wheels 16 at each end of the crane. This may be expeditiously accomplished by providing a drive shaft 23 extending parallel to the side beam 8, as clearly shown in Figure 1, and operatively connecting the same to the axles 15 of two of the flanged wheels 16. One form of driving 105 connection for this purpose is indicated in dotted lines in Figure 5, and comprises a flanged coupling 24 carried by the extended end 25 of the axles 15 to which connection is to be made.

110 In Figure 7 the shaft 23 is illustrated as provided with a flanged coupling 26 adapted to cooperate with the coupling 24. This shaft may obviously be constructed in sections, and the sections in turn connected by 115 similar flanged coupling members 27. This makes it possible to carry in stock lengths of shafting which may be assembled, as required.

120 In Figures 7 and 8 of the drawings, there is illustrated the operating mechanism for the shaft 23. This mechanism may comprise a worm wheel 28 keyed to one of the sections of the shaft 23 and driven by a worm 29 carried by the short shaft 30. The shaft 30 has 125 secured to one end thereof a gear 31 meshing with and driven by a pinion 32 on the armature shaft 33 of the bridge crane moving motor 34. This motor may advantageously be supported in position by securing to the 130

brace 11' a depending plate 35, and providing a supplemental brace 11^a, connecting only the side beam 8 and the center beam 10 as shown in Figure 1, and carrying a second plate 36. Extending between the plates 35 and 36 and secured thereto in any desired manner, as by angle brackets 37, is a motor platform 38. As shown in Figure 7, the brace 11' may carry a bearing 39 for one of the shaft sections 23. It will be apparent that any number of such bearings carried by the braces 11 may be provided.

In order to expedite the assembly of the bridge moving mechanism, the operating parts may conveniently be enclosed in a casting comprising a lower section 40 and an upper section 40^a, these sections having their division line substantially coinciding with the center line of the shafting 23. The top section 40^a may have the bearing 41 for the short shaft 30 secured thereto in any desired manner, as by the provision of transversely extending bolts 42 passing through suitable openings in the bearing 41, whereby it is bodily removable.

With the construction described, it will be apparent that when the bridge motor 34 is energized, it will be effective for moving the entire crane or bridge on the tracks 7. When the motor is de-energized, the worm driving connection provided will constitute an automatic lock preventing accidental movement of the bridge from the desired position.

Carried by the bridge crane is an annular track 43 constituting part of the trolley construction. This track permits the furnace charging tongs to be rotated or turned to any desired position. This track, as illustrated in Figure 2, may conveniently be formed by bending an I-beam of the desired length into circular shape. For operatively securing the track 43 to the bridge, there may be provided a series of brackets 44, as clearly shown in Figures 2, 9, 11 and 12, which brackets carry wheels 45 mounted on suitable stub axles in the brackets in spaced relation, as shown, and adapted to travel on the respective bridge beams 8, 9 and 10. This construction permits relative movement between the track 43 and the bridge, and the brackets 44 may be secured to the top flange of the track 43 in such manner as to securely support the same.

The two brackets 44 which cooperate with the center beam 10, are operatively secured to angle bars 46, as clearly shown in Figures 2, 9, 11 and 12, which bars extend transversely of the track 43 on opposite sides of one of its diameters. As shown in Figures 9 and 10, these angle bars have secured to the intermediate portions thereof suitable stub axles which carry wheels 47 traveling between the flanges of the center beam 10. These wheels may all be provided with suit-

able connecting gear trains 48 for causing the same to rotate in unison. For driving one of the gear trains and thereby positively moving the rotating support or trolley longitudinally of the bridge, there is provided a trolley motor 49, the armature of which carries a pinion 50 meshing with one of the gears of a second gear train 51, the last gear of which is in mesh with one of the gears of one of the trains 48. With this construction, it will be apparent that when the trolley motor 49 is energized, it will positively rotate the wheels 47 and thereby propel the trolley longitudinally of the bridge. The angle bars 46 maintain at all times the desired relationship between the respective parts of the trolley whereby the trolley motor and its associated mechanism is maintained substantially centrally of the annular track 43.

Carried by the trolley propelling wheels 47 is a hoisting mechanism for the billet engaging tongs, which mechanism will now be described. As illustrated in Figures 2, 10, 13 and 14, the wheels 47 may carry spaced supporting brackets 52 projecting downwardly therefrom and secured at their lower portions to the upper half 53 of a housing for the worm wheel 54 which actuates the hoisting drum 55. This hoisting drum may conveniently be formed of a tubular member having cable guiding grooves 56 formed in its periphery adjacent the end portions thereof and having openings 57 to receive the cable ends. These cable ends may in turn be clamped in any desired manner to projections 58 provided for that purpose. Adjacent its central portion the drum 55 is provided with a projecting flange 59 to which the worm wheel 54 may be operatively secured.

For driving the worm wheel 54 and thereby rotating the hoisting drum, there may be provided a worm 60 mounted in a suitable bearing 61 in the lower half 62 of the housing for the worm wheel 54. The bearing 61 may be of a bodily removable construction similar to that described in connection with the bridge operating motor and as shown more particularly in Figure 8. The worm 60 is in turn driven by a hoist motor 63 having a driving pinion 64 meshing with the gear 65 operatively secured to the worm 60. The hoist motor may conveniently be mounted on a bracket 66 secured to and projecting from the lower portion 62 of the housing.

The hoisting drum 55 may advantageously be rotatably supported on a plurality of spaced rollers 67 arranged in sets with each set secured to a spacing ring 68. The spacing rings are of such diameter that the rollers will be held in position to directly engage the outer surface of the hoisting drum adjacent the flange 59. For this purpose, I

find it desirable to suitably harden the surface of the hoisting drum at these portions to provide hardened trackways as indicated in Figure 14. Surrounding the sets of rollers 67 and forming outer tracks therefor are suitable thrust and bearing rings 69, these rings being inserted into the housing sections 53 and 62 and held in position by shoulders 70 formed thereon. These shoulders terminate on the lower housing section 62 providing a short space permitting the easy insertion or removal of the worm 60 and its bearing 61.

The hoisting mechanism described constitutes what may be termed a unit construction or assembly, as the entire mechanism may obviously be separately assembled and then bodily secured in position by attaching the upper housing section 53 to the brackets 52. This permits the units to be carried in stock ready for assembly.

In Figures 15, 16 and 17, there are illustrated different portions of the furnace charging tongs, the relationship of the parts 25 when in assembled position being illustrated in Figure 2. These tongs may be of any well known construction comprising a suitable supporting casing 71 having extending therethrough a gripper operating rod 30 72 secured at its outer end in a head 73. This head has an operating connection 74 with the inner ends of pivotally mounted grippers 75 whereby reciprocation of the rod 72 will be operative for opening and 35 closing the grippers to thereby release or engage a billet. The rod 72 may conveniently be moved in different directions by the provision of a grip operating motor 76 mounted on a platform 76' secured to a 40 transversely extending beam 77, which beam is operatively secured to, and serves as a support for, the rear end of the tong casing 71. The grip operating motor 76 has secured to its armature a pinion 78 (see 45 Figure 3) which meshes with a gear 79 which is keyed to a sleeve 80 projecting into the rear end of the tong casing 71. This sleeve extends through bushings 81 formed in the casing and permitting rotation of the sleeve. Secured to the sleeve for rotation therewith is an internally threaded member 82 engaging the threads 83 on the rear portion of the operating rod 72. With this construction, it will be 50 apparent that as the gear 79 is rotated, it will effect reciprocable movements of the rod 72, thereby either opening or closing the grippers.

The beam 77, as shown in Figures 3 and 60 18, has secured thereto a plurality of rearwardly extending plates 84 at each end. Extending through these plates at each end of the beam and projecting therebeyond are supporting pins 85. These pins may be 65 secured against rotation in the plates 84 by bolts 86 and are journaled at their outer ends in bearings 87 secured to uprights 88 projecting upwardly from the operator's platform 89. These uprights may be secured at their upper ends by a transversely 70 extending beam 90.

For operatively supporting the tongs from the trolley carried by the bridge, the cable carried by the hoist drum may extend around sheaves in a sheave block 91 carrying a swiveled supporting hook 92. This hook may carry a chain 93 connected at its lower end to a yoke 94 pivotally secured to the casing 71. With this construction, operation of the hoist motor 63 80 will raise or lower the sheave block 91 and thereby correspondingly raise or lower the front end of the tongs. This movement will result in a pivotal movement of the rear portion of the tongs about the 85 pins 85.

It is also essential to support the operator's platform from the trolley so that it may be moved in unison with the tongs for the purpose of transferring a billet from 90 one point another. This may conveniently be accomplished by providing a short beam section 95, as illustrated more particularly in Figures 2, 11 and 12 and supporting the same from the track 43 by brackets 96 carrying wheels 97 engaging and traveling on the lower flange of the annular track. Secure 95 in any desired manner to the ends of the beam 95 are chains 98 extending downwardly in diverging relationship, and connected to the ends of the upper beam 90 of the operator's platform.

In order to permit the tongs to be bodily rotated about a vertical axis, to move the same into the desired co-operative position 105 with respect to a billet, a furnace, a roll table or the like, there may be provided a turning motor 99 (Figures 11 and 12) suspended from the short beam 95 and having a driving pinion 100 meshing with a gear 110 101 on the stub shaft 102 journaled in one of the brackets 96. This shaft carries gears 103 meshing with gears 104 on certain of the wheels 97 for rotating the same. Under the influence of the turning motor 99 the operator's platform may be bodily rotated, thereby rotating the gripper tongs. As the hoisting mechanism during such rotational movement remains stationary except for the 115 twisting of the electric cable described hereinafter and the swiveling of the hook 92, it is desirable to prevent the operator's platform from being movable through more than one complete or substantially complete revolution in each direction. For this purpose the short beam 95 may have secured thereto a block 105 adapted to engage a fixed stop 106 (see Figure 12) secured to the lower side of the annular track 43. This permits the turning motor 99 to move the 120 125 130

parts through substantially one complete revolution, but prevents continued rotational movement beyond predetermined points in either direction.

5 While it will be apparent that several different forms of controls for the various motors may be provided, it is desirable that means be present in an apparatus of this character for controlling all of the various 10 motors from the operator's platform. In Figures 2, 3 and 19, there is illustrated more or less diagrammatically one arrangement of controls for this purpose. The controller 107 may control the supply of current to the 15 bridge motor 34; the controller 108 may control the supply of current to the hoist motor 63; the controller 109 may control the supply of current to the trolley motor 49; the controller 110 may control the supply of 20 current to the grip motor 76 and the controller 111 may control the supply of current to the turning or rotating motor 99.

For supplying current for operating the respective motors irrespective of the position of the bridge or trolley, there may be provided a pair of conductors 112 of any usual construction extending substantially parallel to one of the bridge tracks 7 and be energized from line wires L and L'. Brush 25 contacts 113 may engage the conductors 112 and deliver current to a pair of angle bars 114 extending longitudinally of the bridge and carried by and insulated from the bracing 30 11 as clearly shown in Figure 2. Extending parallel to the angle bars 114 are four other angle bars 115 for conducting current to the field and armature of the bridge motor 34 whereby the operation of the motor may be reversed.

40 Extending downwardly from the trolley from substantially the central point thereof is a main cable 116 containing the wires through which current may be conducted to the respective controllers and the motors controlled thereby. This may be accomplished by providing brush contacts 117 for a pair of conductors 118 having connections 119 leading to each of the controllers. The controllers 107, 109, 110 and 111 may be of 45 substantially similar construction each having an operating handle connected to a reversing switch, as indicated diagrammatically in Figure 19. It will be understood that movement of the operating handle in one direction is effective for causing the motors controlled thereby to rotate in one direction while movement of the handles in the opposite direction effects a reversal of the motors. With the handles in neutral 50 position the motors would be de-energized. As the construction of these controllers and the wiring therefor may be of any well known construction, they will not be referred to in detail herein, but are indicated 55 merely for the purpose of enabling a clear

understanding of the operation of my improved furnace charger.

In connection with the hoist motor 63 there may be provided an electric brake 120 (see Figures 10 and 19), which brake is 70 adapted to be automatically de-energized and thereby applied when the hoist motor is de-energized, and energized and rendered inoperative when the hoist motor is energized. This may be accomplished by providing separate contacts 121 in the controller 108 adapted to be engaged when the controller handle is in operative position for holding the brake released when the hoist motor is operating, and to be disengaged 80 when the controller handle is moved to neutral position as indicated in Figure 19 and thereby render the brake operative.

In some instances, it may be desirable to provide a modified form of turning mechanism adapted to rotate the trolley to the desired position with respect to the annular track 43. In Figures 20, 21 and 22, there is illustrated such a mechanism in which the wheels 97', which engage the lower flange of the I-beam track 43 are positively driven by a shaft 125. This shaft has secured to one end thereto a gear 126 meshing with a pinion 127 on a second shaft 128. This second shaft is in turn driven by a turning 95 motor 99' in a manner similar to that illustrated in Figures 11 and 12.

The main advantage of the construction illustrated in Figures 20 to 22, over that before described, resides in the provision of a driving wheel 129 secured to the shaft 125 and adapted to engage the base of the track 43 when for any reason the trolley tilts in such manner as to tend to raise the wheels 97' out of driving engagement with the track. In this manner a positive driving relationship between the trolley and the annular track is continuously maintained.

In Figures 23, 24 and 25, I have shown a modified embodiment of the present invention for the purpose of illustrating the adaptability of the present invention to cranes of standard construction, and its consequent wide range of usefulness. In these figures, there is shown the main center beam 10' of a bridge crane adapted to support the modified trolley which is movable to any desired point longitudinally thereof. This modified trolley may comprise a main beam 130 having secured to one end thereof a bracket 131 for supporting wheels 132. Adjacent its opposite end there is provided a slightly modified form of trolley propelling mechanism. This mechanism is generally similar to that illustrated more particularly in Figures 9 and 10, and comprises a trolley motor 49' having its driving pinion 50' meshing with a gear 51' on a transversely extending shaft 133, which shaft is journaled in the main beam 130. This beam 115

may be either of unitary construction or of composite construction, as illustrated in Figure 23. Secured to this shaft is a pinion 134 meshing with the driving gear 135 on the shaft 136. This shaft in turn carries the pinions which mesh with the driving gears secured in any desired manner to the driving wheels 47.

Carried by the beam 130 and extending downwardly therefrom to any desired point is a king bolt 137. This king bolt may be mounted within a post 138 suitably secured to the main beam 130 and extending downwardly therefrom to provide an elongated support and bearing surface for the king bolt. Surrounding this post are a series of conducting rings 139 which may be permanently connected to a source of electric current. Each of these conducting rings may in turn supply current to the various operating motors and their controllers in well known manner, as by brushes similar to the brush contacts 117 shown in Figure 19.

The conducting rings may be insulated from each other by insulating sections 139¹, and may be held in assembled position by longitudinally extending bolts 137¹ mounted within fiber sleeves as shown.

At its lower end the king bolt 137 carries a thrust bearing 140 upon which is rotatably supported a trolley beam 141. With the arrangement illustrated, it will be apparent that it is possible to swing the trolley beam 141 to various angular positions with respect to the main beam 130. For additionally supporting this trolley beam, it may be provided adjacent one end with a bracket 142 carrying track wheels 143 in supporting relationship to the lower flange of the annular track 43^a secured to the lower side of the main beam 130. The bracket 142 may also carry a supplemental track wheel 144, similar to the wheel 129 shown more particularly in Figure 20, and engaging the bottom of the annular track to prevent undue tilting of the trolley beam.

As a safety device, the trolley beam may also have secured to its opposite end track hooks 145 adapted to normally extend around the lower base flange of the track 43^a and thereby prevent any possibility of falling of the trolley beam in the event of damage to the king bolt or its associated parts.

This construction for certain purposes also possesses a decided advantage over that shown more particularly in Figures 1 to 19. This will be appreciated when it is considered that in the construction of those figures, as shown more particularly in Figure 2, the billet lifting tongs represent in effect a lever of the third class having the point to which power is applied in line with the center of the annular track 43, and the pivotal point of the lever substantially in line with the circumference of said track;

With the arrangement shown more particularly in Figure 24, the trolley beam 141 may have a length substantially equal to the diameter of the annular track. One end of this lever carries chains 98' from which the operator's platform may be suspended, while adjacent its opposite end it carries the hoist motor 63', the hoist drum 55', and their associated parts. This increases the length of the working arm of the tongs, so that it approximately corresponds to the full diameter of the annular track instead of only half of this diameter. In this manner, the load on the hoist motor is decreased, the tongs are more easily operated, the swinging of the tongs is effectively overcome, and the load on the annular track is more nearly balanced. Also with this construction any number of full revolutions in the same direction is made possible.

In Figures 26 and 27, there is illustrated a modified form of charging machine and manipulator. In these figures the crane is illustrated as being of any well known gantry type comprising a horizontally extending frame portion 146 adapted to swing about a center 147. The outer end of the crane may be supported in any well known manner by depending standards 148 carrying track wheels 149 traveling on the arcuate track 150.

The horizontal frame of the gantry crane is preferably of a construction similar to that before described, comprising side beams and a main center beam forming a four-point support for an annular track 43^b. This annular track is illustrated as having secured thereto and projecting downwardly therefrom, a king bolt 151 carrying a trolley beam 152. It will be apparent that the king bolt 151 may be secured to the trolley in such manner that the load thereof is directly transmitted to the center beam of the gantry crane, and through cross struts to the side beams.

With the construction shown in these figures, the trolley beam 152 is preferably of a length slightly greater than that shown more particularly in Figure 24. This construction is advisable for the reason that there is provided a slightly different form of tong operating mechanism making it possible to maintain the tongs at all times in substantially horizontal position whereby a billet carried by the tongs may be maintained in a similar position and so held while being transferred to and operated upon by a forging press 153 or the like. This is highly desirable as it permits the billet to rest in the most efficient position on the anvil of the forging press while being subjected to the action of the press or hammer. In the illustrated embodiment there is secured to one end of the trolley beam a suitable frame 154 carrying the op-

operator's platform 155. Adjacent the opposite end of the trolley beam is secured the hoisting drum 55^a and its associated mechanism. Intermediate the frame 154 and the 5 hoisting drum, and on each side of the trolley beam, is a sheave 156 over each of which passes one strand of a hoisting cable 157. The free ends of this cable pass to the hoisting drum, while the opposite ends 10 may be dead-ended to the trolley beam. The hoisting drum is also adapted to suitably operate a second cable 158 secured at an intermediate point to the billet tongs. By reason of this construction, it will be 15 obvious that upon operation of the hoisting drum 55^a the cables 157 and 158 will be simultaneously wound up or played out, thereby simultaneously moving two spaced points of the billet tongs causing such tongs 20 to travel vertically while maintained truly horizontal.

The billet tongs, with the gantry crane illustrated, may be swung about the axis of the king bolt 151 to any desired position, 25 and may be moved along the frame 146 to the required point for cooperation with the furnace or a forging press, hammer or the like.

In Figure 28 there is illustrated another 30 form of crane using a charging machine and manipulator of the type shown in the figures just described. For sake of brevity, the parts of this figure corresponding to those parts already described in connection with 35 Figures 26 and 27 have been indicated by the same reference characters. The only differences reside in the type of crane, which is here illustrated as being a bridge crane 160, and in the provision of a spacer frame 40 161 between the crane and the trolley beam 152. This spacer frame, which may be constructed in any desired manner, permits the use of the charging machine and manipulator with cranes of various sizes, heights, dimensions, etc., without changing in any respect the construction of the manipulator itself. It will be apparent that the spacing frame may itself be adapted to cooperate 45 with a standard or special crane at its upper end and carry the improved apparatus at its lower end. This spacing frame may be used not only with bridge cranes, as illustrated herein, but with gantry cranes or fixed overhead tracks, as will be clearly apparent.

50 In Figures 29 and 30, there is shown a form of apparatus particularly adapted for use as an ingot or billet manipulator. In this form of the invention there is provided a supporting frame 163 of any desired construction carrying an overhead track 164 on which is adapted to travel a modified form 55 of trolley 165. This trolley so far as its propelling motor 50^c and its hoist motor 63^c are concerned, may be of the identical unit

construction illustrated in Figure 10. This 65 clearly illustrates the range of usefulness of this unit construction and the flexibility possible in the selection and arrangement of parts. The trolley may be of any desired length and may carry at its opposite end a 70 suitable arrangement of wheels 166 for carrying sheaves 167 for the hoisting cables. With this apparatus there may be provided two cables, as before described, for maintaining the tongs 168 in such position that the billet or ingot B is always presented to the operating press or hammer 169 in a true 75 horizontal position.

In Figure 31 there is illustrated a construction embodying an operator's platform 80 89', similar to that of Figure 2, carried by a trolley beam 152', similar to that shown in Fig. 27. This may be carried by a king bolt 151 for cooperation with an annular track 170. The trolley beam may be provided with a bracket 142', and track hooks 145' as described in connection with the crane shown in Figure 24. This entire structure is illustrated as spaced from the carrying crane 171 on the bridge 172 by a 90 spacer 173. This spacer, while functioning like the spacer 161, is of tubular shape. This provides a construction which may be 95 easily assembled, and permits the spacers to be carried in stock as tubes.

I am aware that it has been proposed to provide cranes generally with annular tracks carrying a rotating frame which supports the hoisting mechanism. With such constructions, however, the weight of the load being hoisted has been carried directly by the annular track thereby subjecting this structure to a considerable strain. The present invention possesses decided advantages over such a construction by providing 100 means cooperating with the annular track and adapted to directly carry the weight of the load being hoisted. It will be apparent that a bridge crane constructed of three beams as illustrated provides a means for 105 rigidly supporting the trolley including the annular track and the load.

Further advantages of the present invention arise from the provision of charging or 110 manipulating apparatus composed of a series of units permitting great flexibility in the assembly and manner of use thereof and enabling standard parts to be carried in stock for assembly in accordance with the specifications, immediately upon receipt of 115 an order. This greatly expedites the construction and operation of the apparatus and enables the apparatus to be furnished at a lower initial cost and in a much less period of time.

Still further advantages arise from the provision of an apparatus of this character adapted for use either with special or stand-

ard cranes, and of extremely light weight as compared with apparatus heretofore provided for the same purpose.

Still another advantage arises from the use of a unit power mechanism comprising a bearing, adapted to be bodily removed and replaced, and having a shaft extending therethrough with a worm mounted thereon and partly enclosed by the bearing. On one end of the shaft is a spur gear. All of these parts are assembled as a unit including all thrust and roller bearings whereby after the unit has once been assembled, it may be bodily removed or inserted with its associated parts without disturbing any of the accurately adjusted bearings.

The modified forms illustrated in the drawings show that the invention may be embodied in different mechanical constructions within the scope of the following claims.

I claim:

1. In a billet handling apparatus, a crane comprising side beams and a center beam, and an annular track operatively supported by all of said beams and lying in a position below the same, substantially as described.
2. In a billet handling apparatus, a crane comprising side beams and a center beam, an annular track operatively supported by all of said beams and lying in a position below the same, and in spaced relation thereto, substantially as described.
3. In a billet handling apparatus, a crane comprising side beams and a center beam, supporting means for said crane, and an annular trackway operatively supported below said beams and movable longitudinally thereon, substantially as described.
4. In a billet handling apparatus, a crane comprising side beams and a center beam, supporting means for said crane, and an annular trackway operatively supported below said beams and in spaced relation thereto and movable longitudinally thereon, substantially as described.
5. In a crane, a longitudinally extending beam, an annular trackway supported by and movable longitudinally of said beam, and hoisting mechanism cooperating with said trackway but transmitting its load to said beam independently of said trackway, substantially as described.
6. In a crane, a longitudinally extending beam, and an annular trackway supported by said beam in spaced relation thereto and movable longitudinally of the beam, substantially as described.
7. In a crane, a frame comprising a plurality of beams, a plurality of tubular members, and supporting wheels therefor intermediate said beams and tubular members, substantially as described.
8. In a crane, a plurality of supporting beams, wheel bearing castings operatively

secured to said beams, and tubular members operatively connected to said castings, substantially as described.

9. In a crane, a frame comprising I-beam members extending in one direction, tubular members extending at an angle thereto, and supporting wheels intermediate the ends of the tubular members and said I-beam members substantially as described.

10. In a crane, a frame comprising I-beam side members and tubular end members, and means telescoping with said tubular end members for connecting the side and end members substantially as described.

11. In a crane, supporting beams, an annular track below said beams, and tension means extending upwardly from said track to said beams, said tension means carrying wheels directly engaging said beams, substantially as described.

12. In a crane, supporting beams, an annular track below said beams and in spaced relation thereto, and tension means extending upwardly from said track to said beams and serving as spacing means between the track and beams, said tension means carrying wheels directly engaging said beams, substantially as described.

13. In a crane, side beams, a center beam, an annular track movably suspended from all of said beams, and means for moving said track longitudinally of said beams, substantially as described.

14. In a crane, a longitudinally extending beam, an annular track operatively supported by and movable longitudinally of said beam, means for moving said track longitudinally of said beam, and means for maintaining said track moving means in operative relation to said track, substantially as described.

15. In a crane, a longitudinally extending beam, an annular track operatively supported by and movable longitudinally of said beam in spaced relation thereto, means for moving said track longitudinally of said beam, and means for maintaining said track moving means in operative relation to said track, substantially as described.

16. In a crane, side beams, a center beam, an annular track movably suspended from all of said beams, means for moving said track longitudinally of said beams, and means for maintaining said track moving means in operative relation to said track, substantially as described.

17. In a crane, a frame comprising side beams and a center beam, and an annular track having at least one point of support with the side beams and a plurality of points of support with said center beam, substantially as described.

18. In a crane, a frame comprising side beams and a center beam, and an annular track having at least one point of support

with the side beams and a plurality of points of support with said center beam, said track having a diameter substantially equal to the distance between said side beams, substantially as described.

19. A frame structure for cranes, comprising end castings adapted to receive a wheel axle, and means projecting from said castings for cooperation with tubular frame members, substantially as described.

20. In a crane structure, end casting having angularly disposed faces adapted to receive wheel axle bearings, and tubular members operatively secured to said castings for maintaining the same in predetermined spaced relationship, substantially as described.

21. In a billet handling apparatus, a movable crane, an annular track operatively supported below said crane, means for moving said track longitudinally of the crane, and billet engaging means operatively supported by and transmitting its load directly to said crane independently of said track, substantially as described.

22. In a billet handling apparatus, a crane, means for moving the same, an annular track operatively supported below said crane, means for moving the track longitudinally of the crane, billet engaging means operatively suspended directly from said crane centrally of said track, and an operator's platform suspended directly from said track, substantially as described.

23. In a crane, supporting beams, tubular members operatively secured to said beams and maintaining the same in predetermined spaced relationship, supporting wheels for said crane, a sectional drive shaft extending longitudinally of said crane, and means for rotating said drive shaft, substantially as described.

24. In a crane, a drive shaft, a worm wheel operatively secured thereto, a worm for driving said worm wheel, a housing enclosing said worm wheel and worm, said housing being split on substantially the center line of said shaft, and a bearing removably carried by said housing for maintaining the driving worm in operative position, substantially as described.

25. In a billet handling machine, a crane, an annular track having a four point support with said crane, means for moving said track longitudinally of the crane, and a billet engaging means suspended directly from said crane centrally of said track, to transmit its load to the crane independently of the track, substantially as described.

26. In a billet handling machine, a crane, an annular track having a four point support with said crane, means for moving said track longitudinally of the crane, and a billet engaging means suspended directly from said crane, for transmitting its load to the

crane independently of the track, substantially as described.

27. In a billet handling machine, a crane comprising side beams and a center beam, a track suspended from said beams and movable longitudinally thereof, and billet engaging means directly suspended from said center beam centrally of said track, substantially as described.

28. In a billet handling machine, a crane comprising side beams and a center beam, a track suspended from said beams and movable longitudinally thereof, and billet engaging means directly suspended from said center beam, substantially as described.

29. In a crane, supporting beams, four supporting means substantially equi-distantly spaced and cooperating with said beams, a spacer to which said means are attached, an annular track carried by said spacer, and a material-handling means carried by said spacer but not by said track, substantially as described.

30. In a crane, supporting beams, four supporting means substantially equi-distantly spaced and movable longitudinally of said beams, a spacer to which said means are attached, an annular track carried by said spacer, and a material-handling means carried by said spacer but not by said track, substantially as described.

31. In a crane, supporting beams, four supporting means substantially equi-distantly spaced and cooperating with said beams, a spacer to which said means are attached, an annular track carried by said spacer, a trolley rotatably supported by said track, and a material-handling means carried by said spacer but not by said track, substantially as described.

32. In a crane, supporting beams, four supporting means substantially equi-distantly spaced and cooperating with said beams, a spacer to which said means are attached, an annular track carried by said spacer, a trolley beam extending transversely of the track, and hoisting means on said trolley beam, substantially as described.

33. In a crane, supporting beams, four supporting means substantially equi-distantly spaced and cooperating with said beams, a spacer to which said means are attached, an annular track carried by said spacer, a trolley beam extending transversely of the track, and hoisting means on said trolley beam, said trolley beam having an effective length at least substantially as great as the diameter of said track, substantially as described.

34. In a crane, an annular track, a trolley beam extending transversely of said track, and hoisting means on said beam, substantially as described.

35. In a crane, an annular track, a trolley beam extending transversely of said track,

and hoisting means on said beam, said beam having an effective length at least as substantially as great as the diameter of said track, substantially as described.

5. 36. In a crane, an annular track, a trolley beam extending transversely of said track and rotatable around the axis of the track, and hoisting means carried by said beam, substantially as described.

10. 37. In a crane, an annular track, a trolley beam extending transversely of said track and rotatable around the axis thereof, and hoisting means suspended from substantially opposite ends of said beam, substantially as described.

20. 38. In a billet handling apparatus, a movable crane, an annular track operatively supported below said crane, means for moving said track longitudinally of the crane, a trolley beam rotatable around the axis of said track, and billet engaging means operatively supported by said beam, substantially as described.

25. 39. In a billet handling apparatus, a movable crane, an annular track operatively supported below said crane, means for moving said track longitudinally of the crane, a trolley beam rotatable around the axis of said track, and billet engaging means operatively supported from opposite ends of said beam, substantially as described.

35. 40. In a crane, a frame comprising beam members extending in one direction and tubular members extending at an angle thereto, and means in the plane of said members for connecting the same.

40. 41. In a crane, a frame comprising beam side members and tubular end members, and means telescoping with the tubular members and butting the beam members for connecting the same.

45. 42. In a crane, an overhead support, a spacer projecting downwardly therefrom, an annular track carried by said spacer, and material-handling means connected to said support independently of said track.

50. 43. In a crane, an overhead support, a tubular spacer projecting downwardly therefrom, and an annular track carried by said spacer.

55. 44. In a crane, a trolley, a spacer carried by and projecting downwardly from said trolley, and an annular track carried by said spacer, and material-handling means cooperating with said track but transmitting its load directly to said trolley independently of the track.

60. 45. In a crane, an overhead support, a spacer projecting downwardly therefrom, an annular track carried by said spacer, a trolley rotatably supported at least partly by said annular track, and material-handling means transmitting its load to said spacer independently of said track.

65. 46. In a crane, an overhead support, a

tubular spacer projecting downwardly therefrom, an annular track carried by said spacer, and a trolley rotatably supported at least partly by said annular track.

70. 47. In a crane, a trolley, a spacer carried by and projecting downwardly from said trolley, an annular track carried by said spacer, a trolley rotatably supported at least partly by said annular track, and material-handling means supported by said spacer independently of said track.

75. 48. In a crane, an overhead support, a spacer projecting downwardly therefrom, an annular track carried by said spacer, a trolley beam extending transversely of the track, and hoisting means on the trolley beam.

80. 49. In a crane, an overhead support, a tubular spacer projecting downwardly therefrom, an annular track carried by said spacer, a trolley beam extending transversely of the track, and hoisting means on the trolley beam.

85. 50. In a crane, a trolley, a spacer carried by and projecting downwardly from said trolley, an annular track carried by said spacer, a trolley beam extending transversely of the track, and hoisting means on the trolley beam.

90. 51. A unit power mechanism comprising a bearing adapted to be secured in cooperative relation to a worm wheel, a shaft extending through said bearing, and a worm carried by said shaft and partially enclosed by said bearing.

95. 52. A unit power mechanism comprising a bearing adapted to be secured in cooperative relation to a worm wheel, a shaft extending through said bearing, and a worm carried by said shaft and partially enclosed by said bearing, said bearing having openings formed therein for the reception of fastening means.

100. 53. A unit power mechanism comprising a bearing housing adapted to be secured in cooperative relation to a worm wheel, a shaft extending through said bearing housing, anti-friction bearings for said shaft, a worm carried by said shaft intermediate said anti-friction bearings and partly enclosed by said bearing housing, and means carried by said shaft for rotating said worm, all of said mechanism being bodily removable and replaceable as a unit.

105. 54. A unit power mechanism comprising a bearing housing adapted to be secured in cooperative relation to a worm wheel, a shaft journaled in said bearing housing and having one end thereof projecting beyond said housing for connection with a source of power, and a worm carried by said shaft and partly enclosed by said housing.

110. 55. A unit power mechanism comprising a bearing housing adapted to be secured in cooperative relation to a worm wheel, a shaft

130.

10 journaled in said bearing housing and having one end thereof projecting beyond said housing for connection with a source of power, a worm carried by said shaft and partly enclosed by said housing, and a thrust bearing within said housing for said worm.

15 56. In a crane, a frame comprising a plurality of beams, a plurality of tubular members, and connecting members for said beams and tubular members, said connecting members being shaped at one end to cooperate with said beams and at the other end to cooperate with said tubular members, substantially as described.

20 57. In a crane, a frame comprising a plurality of beams, a plurality of tubular members, and wheel bearings serving to connect said beams and members, said wheel bearings being shaped at one end to cooperate with said beams and at the other end to cooperate with said tubular members, substantially as described.

25 58. In a crane, a frame comprising I-beam members extending in one direction, tubular members extending at an angle thereto, and connecting castings intermediate said beam members and tubular members, substantially as described.

30 59. In a crane, a frame comprising I-beam members extending in one direction, tubular members extending at an angle thereto, and connecting castings intermediate said beam members and tubular members, said connecting castings carrying supporting wheels for the frame, substantially as described.

35 60. In a crane, a frame comprising separable members, and a wheel-carrying unit adapted to connect said members, substantially as described.

40 61. In a crane, a frame comprising a plurality of angularly extending separable members, at least some of said members being tubular, and a wheel-carrying unit adapted to be interposed between a tubular member and an adjacent member for connecting the same, substantially as described.

45 62. In a billet-handling apparatus, a movable crane, an annular track operatively supported by said crane, means for moving said track longitudinally of the crane, and billet-engaging means operatively supported by and transmitting its load directly to said crane independently of said track, substantially as described.

50 63. In a billet-handling apparatus, a crane, an annular track having substantially equidistantly spaced points of support with said crane, means for moving said track longitudinally of the crane, and billet-engaging means suspended directly from said crane centrally of the track to transmit its load to the crane independently of the track, substantially as described.

55 64. In a crane, supporting beams, a plural-

ity of equidistantly spaced supporting means 65 cooperating with said beams, a spacer to which said means are attached, an annular track carried by said spacer, and a material-handling means carried by said spacer for transmitting its load directly to said spacer 70 independently of said track, substantially as described.

65 75 56. In a crane, supporting beams, equidistantly spaced supporting means cooperating with said beams, a spacer to which said means are attached, an annular track carried by said spacer, a trolley beam lying in a plane containing a chord of a predetermined arc of said track, and hoisting means on said trolley beam, substantially as described.

80 75 56. In a crane, supporting beams, equidistantly spaced supporting means cooperating with said beams, a spacer to which said means are attached, an annular track carried by said spacer, a trolley beam lying in a plane containing a chord of a predetermined arc of said track, and hoisting means on said trolley beam, said trolley beam having an effective length at least as great as the diameter of said track, substantially as described.

85 95 57. In a crane, an annular track, a trolley beam lying in a plane containing a chord of a predetermined arc of said track, and hoisting means on said beam, substantially as described.

90 100 58. In a crane, an annular track, a trolley beam lying in a plane containing a chord of a predetermined arc of said track, and hoisting means on said beam, said beam having an effective length at least substantially as great as the diameter of said track, substantially as described.

105 59. In a crane, an annular track, a trolley beam rotatable around the axis of said track, and hoisting means carried by said beam, substantially as described.

110 60. In a crane, an annular track, a trolley beam rotatable around the axis of said track, and hoisting means carried by said beam, said hoisting means being suspended from substantially opposite ends of said beam, substantially as described.

115 61. In a crane, a frame comprising beam members extending in one direction, tubular members extending at an angle thereto, and wheels at substantially the junction of said beam members and tubular members, substantially as described.

120 62. In a crane, an overhead support, a spacer projecting downwardly therefrom, an annular track carried by said spacer, and rotatable about the center of said track as an axis, and hoisting means on said trolley beams, substantially as described.

125 In testimony whereof I have hereunto set my hand.

EDGAR E. BROSIUS.
